UNITED STATES PATENT OFFICE

JOHN R. ANDERSON, OF MOLINE, ILLINOIS.

FOLDING TABLE.

1,252,766.

Specification of Letters Patent. Patented Jan. 8, 1918.

Application filed March 6, 1916. Serial No. 82,879.

To all whom it may concern:

Be it known that I, JOHN R. ANDERSON, a citizen of the United States, residing at Moline, in the county of Rock Island and 5 State of Illinois, have invented certain new and useful Improvements in Folding Tables, of which the following is a specification.

This invention relates to tables and more particularly to a folding table adapted for 10 a variety of uses which is substantial and rigid and presents, when extended, a pleasing appearance.

It is a principal object of my invention to provide a table adapted to fold into a compact bundle occupying a relatively small space when compared with the dimensions 15 of the extended table.

A further object of my invention is the provision of a folding table in which the top 20 as well as the legs may be folded, the legs being disposed at the corners of the table leaving a free space therebeneath.

A further object of my invention is the provision of a table having a folding top 25 and permanently connected folding legs which may be quickly and rigidly disposed in supporting relation to the top with a minimum of effort and without the use of tools.

30 A further object of my invention is the provision of a folding table combining the greatest degree of compactness, when folded, with great rigidity, when extended, without the necessity of employing extended 35 diagonal braces which would mar the appearance and interfere with the utility of the table.

A still further object of my invention is the provision in a table having permanently 40 connected folding legs of means for adjusting the legs to take up any possible wear or shrinkage whereby the permanent rigidity of the table is assured.

Other objects and advantages of my invention will be apparent as it is better 45 understood by reference to the following specification when read in connection with the accompanying drawing illustrating the preferred embodiment thereof in which—

50 Figure 1 is a perspective illustration of the extended table;

Fig. 2 is a view in perspective of one end of the table partially folded;

Fig. 3 is a similar view illustrating the

appearance of the table when completely 55 folded;

Fig. 4 is a view in perspective of the underside of one end of the table illustrating one leg secured in supporting relation to the top and another in an intermediate position; 60

Fig. 5 is a similar view illustrating the legs folded in position to allow the top of the table to be folded;

Fig. 6 is a detail in section of a portion of 65 the top and one of the legs;

Fig. 7 is a detail in elevation of one corner of the table;

Fig. 8 is a vertical section on the line 8—8 of Fig. 7, and

Fig. 9 is a vertical section on the line 70 9—9 of Fig. 7.

Referring to the drawing, the table consists of a top constructed of a plurality of longitudinally extending sections 5 and 6, the sections 5 being of the same width and 75 the sections 6 being of lesser width for reasons which will appear hereafter. The sections 5 and 6 are connected at intervals by hinges 7 secured to the underside of the table top. Rigidly secured to each of the outermost sections 5 are a pair of longitudinally extending members 8 forming channels with the sections 5 which materially strengthen the table top. The legs 9 are hingedly secured to the table top by means of members 85 10 secured to the outermost sections 5 between the longitudinally extending members 8 and connected to members 11 by links 12. The members 11 are mounted to slide on the legs 9, being connected thereto by screws 12' 90 (Fig. 7) secured to the legs 9 and operating in slots 13 in the members 11. The members 11 are provided with inwardly directed portions 14 disposed in suitable openings formed in the legs 9 and provide seats 15 for 95 nuts 16 threadedly engaging bolts 17, the heads 18 of which are disposed within recesses 19 provided in the legs 9. It will be

apparent that as the nuts 16 are rotated against the seats 15 the members 11 will be 100 moved away from the upper ends of the legs. This provides an adjustment whereby wear or shrinkage of the legs 9 may be taken up.

Separable transversely extending members 20 are provided which are adapted to be disposed at each end of the table abutting the ends of the longitudinally extending members 8, as indicated in Fig. 4, the legs 9 being

rabbeted at 21 to provide seats for the members 20. Braces 22 are pivotally connected at 23 to the legs 9 and are provided at their extremities with shoes 24 which adjustably engage members 25 secured to the sections 5 between the longitudinally extending members 8. When the legs 9 are moved to their supporting position, as indicated in Fig. 4, and the shoes 24 are disposed in engagement with the members 25 the transversely extending members 20 will be rigidly clamped in position to support the intermediate sections 5 and 6. Owing to the position of the pivotal points of the legs 9 the pressure applied to the ends thereof in securing the legs in supporting position is enormously multiplied at the point of engagement of the legs 9 with the transversely extending members 20 and hence the rigidity of the structure is assured. Any looseness due to wear or shrinkage may be taken up by operating the nuts 16 in the manner previously described. Auxiliary transversely extending members 26 are secured by hinges 27 to one of the longitudinally extending members 8 at one side of the table and are adapted to be moved to the position indicated in Fig. 4 to engage locking devices 28 on a longitudinally extending member 8 at the opposite side of the table. The auxiliary members 26 provide sufficient support for the sections 5 and 6 between the transversely extending members 20.

The normal position of the parts of the table when in use is indicated in Fig. 1. When the table is no longer desired it may be rapidly folded in the following manner. The table is first turned to the position indicated in Figs. 4 and 5 with its top resting on a supporting surface. The shoes 24 of the braces 22 are released from the members 25 and the legs 9 are folded as indicated in Fig. 5. The auxiliary transversely extending members 26 are moved to the position indicated in Fig. 5 and the transversely extending members 20 are withdrawn and placed in the channel formed by the longitudinally extending members 8 and the outermost sections 5, as indicated in Fig. 6, the ends of the members 20 being retained in position by the ends of the legs 9. The outermost section 5 at the side of the table is folded to a vertical position and then to the position indicated in Fig. 2. It will be noted that the narrower sections 6 are of sufficient width to form the sides of an inclosing structure for the longitudinally extending members 8 and the legs 9. The operation is repeated on the other side of the table and the sections are finally folded to the position indicated in Fig. 3, in which position they may be held by suitable fastening means, if desired, and the table may be stored in a minimum of space.

It will be readily appreciated that my improved folding table may be constructed of wood, metal or any other suitable material.

I have combined in my table the desirable features of great compactness when folded, since the folded table occupies a space but slightly greater than the volume of its parts, with rigidity and appearance equal to that of non-folding tables. It will be noted that the space beneath the table is entirely free from extended diagonal braces and that therefore my table may be employed for any purposes for which ordinary non-folding tables are adapted.

It will be apparent that various changes may be made in the form, construction and arrangement of the parts without departing from the spirit and scope of the invention, or sacrificing any of its material advantages, the form hereinbefore described being merely a preferred embodiment thereof.

I claim:

1. A folding table consisting of a top comprising a plurality of longitudinally extending hingedly connected sections and a longitudinally extending member secured to the underside of each of the outermost sections of said top, supporting legs hingedly connected to said outermost sections, means for securing said legs in supporting position, and transversely extending members adapted to be engaged and clamped by said legs against the ends of said longitudinally extending members and in engagement with the intermediate sections of said top.

2. A folding table consisting of a top comprising a plurality of longitudinally extending hingedly connected sections and a longitudinally extending member secured to the undersides of the outermost sections of said top, supporting legs hingedly connected to said outermost sections, means for securing said legs in supporting position, transversely extending members adapted to be engaged and clamped by said legs against the ends of said longitudinally extending members and in engagement with the intermediate sections of said top, and auxiliary transversely extending members to support said intermediate sections between said first-mentioned transversely extending members.

3. A folding table consisting of a top comprising a plurality of longitudinally extending hingedly connected sections and a longitudinally extending member secured to the undersides of the outermost sections of said top, supporting legs hingedly connected to said outermost sections, means for securing said legs in supporting position, transversely extending members adapted to be engaged and clamped by said legs against the ends of said longitudinally extending members and in engagement with the intermediate sections of said top, and auxiliary transversely extending members hingedly connected to one of said longitudinally extending members and adapted to engage the other to support said intermediate sections between said

first-mentioned transversely extending members.

4. A folding table consisting of a top comprising a plurality of longitudinally extending hingedly connected sections and a pair of longitudinally extending members rigidly secured to the undersides of each of the outermost sections of said top, supporting legs, hinges connected to said legs at points spaced from the upper ends thereof and to said outermost sections, means for securing said legs in supporting position, transversely extending members adapted to be engaged and clamped by said legs against the ends of said longitudinally extending members and in engagement with the intermediate sections of said top, and auxiliary transversely extending members to support said intermediate sections between said first-mentioned transversely extending members.

5. A folding table consisting of a top comprising a plurality of longitudinally extending hingedly connected sections and a pair of longitudinally extending members rigidly secured to the undersides of each of the outermost sections of said top, supporting legs, hinges connected to said legs at points spaced from the upper ends thereof and to said outermost sections, means for securing said legs in supporting position, transversely extending members adapted to be engaged and clamped by said legs against the ends of said longitudinally extending members and in engagement with the intermediate sections of said top, and auxiliary transversely extending members hingedly connected to one of said longitudinally extending members and adapted to engage another at the

opposite side of the table to support said intermediate sections between said first-mentioned transversely extending members.

6. A folding table consisting of a top comprising a plurality of longitudinally extending hingedly connected sections, legs, hinges secured to said legs at points spaced from the upper ends thereof and to said top, means for securing said legs in supporting position, and means for adjusting said legs relatively to said hinges.

7. A folding table consisting of a top comprising a plurality of longitudinally extending hingedly connected sections, legs, hinges connected to said legs at points spaced from the upper ends thereof and to said top, transverse members adapted to be held in supporting relation to the intermediate sections of said top by said legs, means for securing said legs in supporting position to clamp said members, and means for adjusting said legs relatively to said top and transverse members.

8. A folding table consisting of a top comprising a plurality of longitudinally extending hingedly connected sections, a plurality of supporting legs, hinges secured to said top and provided with members slidably engaging said leg, a bolt operatively engaging each leg, and a nut on each bolt operatively engaging the slideable member of the hinge whereby the position of the latter may be varied to adjust said legs with respect to said top.
